ADHESIVE GUN

Roy H. Stein, 3920 Zephyr St., Wheat Ridge, Colo.

Filed Oct. 4, 1965, Ser. No. 87,301

Term of patent 14 years

(Cl. D54—13)

FIG. 1 is an elevational front view of an adhesive gun showing my new design.

FIG. 2 is an elevational side view thereof.

FIGS. 3 and 4 are top and bottom views, respectively, thereof; and

FIG. 5 is an elevational rear view thereof.

I claim:

The ornamental design for an adhesive gun, substantially as shown.
